C. Harpman Attorney

UNITED STATES PATENT OFFICE.

CHARLES E. BAILEY, OF YOUNGSTOWN, OHIO.

PROCESS OF SEPARATING METAL PLATES.

1,334,584.

Specification of Letters Patent. Patented Mar. 23, 1920.

Application filed May 24, 1919. Serial No. 299,665.

To all whom it may concern:

Be it known that I, CHARLES E. BAILEY, citizen of the United States, residing at Youngstown, in the county of Mahoning and State of Ohio, have invented certain new and useful Improvements in Processes of Separating Metal Plates, of which the following is a specification.

This invention relates to the separation of 10 sheets of metal which are caused to adhere with more or less tenacity by some step or treatment in the process of their manufacture.

In order to illustrate the principles involved, the case of steel sheets, such as are used in the manufacture of the socalled "tin plate" will be considered although it will be understood that the method and devices which are applicable here may also be used 20 with the proper modifications in many other cases where metal sheets require separation.

In the process of manufacturing steel plate there is a step after the steel has been rolled down to a certain thickness in which 25 it is folded double upon itself several times and the entire pack afterward rolled thereby reducing the thickness of each sheet uniformly until the individual sheets have the required thickness. This is, of course, done 30 while the pack is hot, and as a result of the combined heat, pressure and rolling, the sheets become fastened together, partly due to the very intimate contact between the adjacent plates, or the forming of an incipient weld, which generally extends only 35 over a portion of the contacting surface.

In the present process of manufacture, after the plates have been reduced in thickness as far as desired, they are separated by 40 a slow and expensive hand process, cleaned, pickled and placed in stacks for annealing. After annealing they are removed from the annealing ovens, cleaned, pickled and separated and again rolled, usually cold, thus 45 producing the finished plate ready for the application of tin, zinc or the galvanizing process.

From this description it will be evident that present commercial processes usually 50 require the stacks of plates to be opened twice in the course of the manufacture of the sheets and that the hand process now in use is slow, and expensive besides producing considerable scrap.

55 The object of this invention is therefore

to provide a simple, quick and inexpensive method of separating the plates.

A further object of the invention is to provide a frame carrying bed rollers, the same used to draw the pack over a right angled shoulder thereby causing the pack to pass through two right angled turns.

A further object is to provide changeable friction corners.

A still further object is to provide means 65 for adjusting the degree in which the pack must be bent in passing under and over the two right angles used in the process of destroying the adhesion between the sheets.

The invention may be put into practice by 70 an apparatus substantially as shown in the accompanying drawing, wherein:

Figure 1 is a sectional side view with the exception of the side rollers.

Fig. 2 is a detail perspective view showing 75 path over which the pack must pass when drawn through by the bed rollers.

Fig. 3 is a perspective detail view of depressing arm.

In the drawings, 1 designates the machine 80 frame. 2 are shafts supporting the depressing arms 3. 4 indicates the bed rollers located between the frame parts 1 of the device.

By referring to Fig. 2 it will be seen that a 85 bed 5 rests upon a support 6 of the lower portion of the frame 1. When desired these bed plates 5 may be adjusted by means of the varying thickness of the plates used or by using fillers between supports 6 and the 90 under side of the bed plates 5. It will also be seen by referring to Fig. 2 that I have provided removable friction corners 7 which are dove tailed into the shoulders 8. These friction corners 7 are provided with detachable and reversible plates 9 held in place by lugs 10.

Fig. 3 shows the depressing arms 3 also equipped with friction corners 7 which are in turn supplied with detachable and reversible plates 9. When it is desired to give the pack less than a double bend I have provided adjusting blocks 11 as shown in Fig. 2 which come in contact with the depressing arms 3 when the same are drawn toward the 105 shoulders 8 as shown in Fig. 1 when the pack 12 is being pulled through the machine by means of the bed rollers 4. It will be obvious that the adjusting blocks 11 may be adjusted by means of fillers placed between 110

the inner sides of adjusting blocks 11 and the adjacent surfaces supporting the same. These adjusting blocks 11 are located at the outer ends of the shoulders 8.

5 In operation the depressing arms 3 are swung outwardly. The pack 12 is fed from the left through the opening 13 until gripped by the bed rollers 4 which carry it on through to point X. The rollers are then 10 stopped, reversed, and the depressing arm 3 is swung downwardly, the pack 12 is caused to be drawn over the shoulder 8 thereby causing the pack to pass through double and opposite bends. The rollers continue to pull 15 the pack 12 to the left as shown in Fig. 1 until the right end of the pack 12 reaches the point Y of the bed rolls 4. At this point the rolls are reversed and the pack 12 again travels to the right. During this process 20 the left depressing arm 3 is lowered before the left end of the pack 12, which remains unopened, has passed the opening 13.

In order to make the operation clear it may be said that when the bed rolls 4 are 25 pulling the pack to the right the right arm is swung outwardly and remains so. When the pack is being pulled through the bed rolls 4 to the left, the left depressing arm is swung outwardly and remains so, or the

right arm is lowered when the pack is being drawn to the left and vice versa.

What I claim is:—

1. In a device of the class described, a frame portion provided with shoulders at each end of the lower portion, bed rolls located within said frame, and depressing arms pivotally swung so as to engage said shoulders, the above mentioned rolls thereby drawing the pack of sheets through a fixed path thereby giving the pack double 30 and opposite bends.

2. In a device of the class described, a frame portion provided with shoulders at each end, bed rolls located within said frame, depressing arms pivotally mounted to swing 35 so as to engage said shoulders, the above mentioned rolls thereby drawing the pack of sheets through a fixed path thereby giving the pack double and opposite bends, a reversible and detachable plate, an adjustable bed plate, and means for adjusting the swing of the depressing arms.

In testimony whereof I affix my signature.

CHARLES E. BAILEY.
